DESIGN.

A. L. FISHER.
BOTTLE CAP.

No. 19,854.

Patented May 27, 1890

UNITED STATES PATENT OFFICE.

ALVIN L. FISHER, OF NEW BRUNSWICK, NEW JERSEY.

DESIGN FOR A BOTTLE-CAP.

SPECIFICATION forming part of Design No. 19,854, dated May 27, 1890.

Application filed May 1, 1890. Serial No. 350,203. Term of patent 7 years.

To all whom it may concern:

- Be it known that I, ALVIN L. FISHER, a citizen of the United States, residing at New Brunswick, in the county of Middlesex and State of New Jersey, have invented and produced a new and original Design for Bottle-Caps, of which the following is a specification, reference being had to the accompanying drawing, forming part thereof.
- 10 My design is illustrated in the accompanying drawing, which represents a perspective view.
- 15 The leading features of my design consist of an ogee-shaped edge formed at the top of the body, spiral beads extending round the body, concave niches extending from the top edge of the body across the spiral beads, and narrow grooves between the concave niches and running parallel with the same.
- 20 A is the body of my bottle-cap, and B is its top, the edge a of which is ogee-shaped, and

the face of which is ornamented by concentric beads b b. The body A is ornamented by spiral beads c c and by concave niches d d, which extend from its top edge across the spiral beads. Between the concave niches and parallel with the same are narrow grooves e e.

What I claim as new, and desire to secure by Letters Patent, is—

25 The design for a bottle-cap herein shown and described, the same comprising the body A, the top B, the ogee-shaped edge a, the spiral beads c c, the concave niches d d, and the narrow grooves e e between the niches, as set forth.

30 In testimony whereof I have hereunto set my hand in the presence of two subscribing witnesses.

35 ALVIN L. FISHER.
